UNITED STATES PATENT OFFICE.

IRA M. KELTNER, OF CARROLLTON, MISSOURI.

RAILWAY-SWITCH.

No. 901,711.

Specification of Letters Patent.

Patented Oct. 20, 1908.

Application filed November 25, 1907. Serial No. 403,672.

To all whom it may concern:

Be it known that I, IRA M. KELTNER, a citizen of the United States, residing at Carrollton, in the county of Carroll and State of Missouri, have invented certain new and useful Improvements in Railway-Switches, of which the following is a specification.

This invention relates to railway switches and has for its object to produce a switch 10 which is automatically opened by a train passing the switch on the main track and which automatically closes after the passage of such train to permit the same to back or another train to pass onto the switch or to 15 permit a train on the switch to pass out thereof and onto the main track.

A further object is to produce means whereby the switch may be manually opened, to permit a train to continue on the main 20 track instead of passing onto the switch.

With these general objects in view and others as hereinafter appear, the invention consists in certain novel and peculiar features of construction and organization as hereinafter 25 described and claimed; and in order that it may be fully understood reference is to be had to the accompanying drawings, in which,

Figure 1, is a top plan view of a railway switch embodying my invention, the switch- 30 stand being shown in section. Fig. 2, is a side view of the construction disclosed by Fig. 1. Fig. 3, is an enlarged section taken on the line III—III of Fig. 1. Fig. 4, is an enlarged section taken on the line IV—IV of 35 Fig. 1. Fig. 5, is a section taken on the dotted line V of Fig. 4. Fig. 6 is a fragmentary section taken in the same plane as Fig. 3, with certain of the parts shown in a different position of adjustment.

40 In the said drawings 1 indicates the cross ties.

2 indicates the stationary rail and 3 the movable rail of the main track section.

45 4 indicates the stationary rail of the switch track section, said rail beyond the point of rail 3 forming part of the main track as usual; and 5 indicates the movable rail of the switch-track section.

50 6 indicates a bracket secured to the cross tie underlying the free end of rail 3.

55 7 is one member of an extensible cross-bar, said member being reduced to provide shoulder 8 and the reduced portion 9 which extends slidingly through bracket 6 and is provided at the side of the bracket occupied by rail 3 with a head 9^a rigidly secured as shown

at 9^b or otherwise to said rail 3. The member 7 is also secured as shown at 10 or otherwise to rail 5. By this arrangement it will be seen that longitudinal movement imparted to member 7 in one direction will open the switch by moving rail 3 toward and against rail 4 and rail 5 away from rail 2 and incidentally effect compression of spring 11 mounted on portion 9 of member 7 and bearing at its opposite ends against shoulder 8 and bracket 6, said spring being sufficiently powerful to restore the rails 3 and 5 to their original position as hereinafter explained. The member 7 is provided outward of rail 2 70 with an opening 12 and fits slidably in the tubular inner portion of the outer member 13 of the cross-bar. Member 13 is reduced at its outer end to form the outwardly disposed shoulder 14 and the reduced portion 15 75 projecting beyond the same and fitting slidably in bracket 16 carried by the adjacent cross-tie. The member 13 is provided in its lower edge by preference with teeth 17 so as to constitute a rack-bar, and pivotally carries at 18 a lever 19. A spring 20 secured to said member presses the lever upward so as to hold its pivotally pendent pin 21 normally in engagement with the opening 12 in member 7. 80

85 22 indicates a link-bar pivotally connecting member 7 with the crank arm 23 of the switch-stand shaft 24, 25 indicating the frame of said stand and 26 the usual or any preferred type of lever for operating said shaft.

90 27 indicates a gear wheel meshing with the rack-bar member 13 and secured upon a shaft 28 journaled at its opposite ends in bearings 29 and 30 secured to cross-ties at 95 suitable distances apart.

95 31 is a bevel gear secured upon shaft 28 and meshing with a vertically arranged rack-bar 32 provided with a stem 33 fitting slidably in a tubular thimble 34 secured in the 100 underlying cross-tie.

105 The rack-bar 32 is secured by a pin 35 to a pair of lugs 36 projecting outwardly from a pair of levers 37 occupying a recess 38 formed in the outer side of rail 2 and pivoted at their remote ends to said rail as at 39, brackets 40 secured to certain ties being disposed at the outer sides of levers 37 to coöperate with rail 2 in guiding them in their pivotal movement.

110 The levers 37 normally slope upwardly from their pivoted ends to a plane above the tread-surface of rail 2 and at their contigu-

ous ends are pivotally connected by a pin 41 to compel them to work in unison, it being noted that the hole 42 in which pivot 41 is arranged, is elongated so as to accommodate 5 the pivotal movement of the levers; it being further noted that the inner and outer faces of the levers occupy the same vertical planes by providing one of them with a bifurcation 10 43 and the other with a tongue 44 engaging said bifurcation. (See Fig. 5).

Assuming that the parts are arranged as shown and that a train is traveling on the main track section in the direction indicated by the arrow, Fig. 1, it will be apparent that 15 the wheels of the first car will ride upon one of the levers 37 and consequently force the same and the companion lever 37 downward. This action imparts like movement to rack-bar 32 and hence through the gearing de- 20 scribed forces the extensible cross bar in the direction indicated by the contiguous arrow Figs. 1 and 3, so as to overcome the resistance of spring 11 and move the rails 3 and 5 against rail 4 and away from rail 2 respectively, so 25 that a train may pass onto the main track without interference on the part of the switch. As the last car passes the switch, the spring 11 returns said parts to their original positions, that is to say, recloses the 30 switch. In the event that a train which should continue on the main track is approaching the closed switch, it is necessary for the switchman to open the switch and this he accomplishes by grasping the switch- 35 stand lever 36 and turning the same. By this action he performs the same function that the train performed by depressing the levers 37. Should the switchman find it impossible to perform such operation because 40 of the levers being frozen in their elevated position, he places his foot upon and de- presses lever 19 so as to withdraw pin 21 from opening 12, and then operates lever 26 and 45 through the medium of link 22 operates the member 7 of the cross bar and opens the switch. After the train has passed he re- leases lever 26 or unlocks it if he has locked 50 it in its new position, so as to permit spring 9 to reclose the switch, it being noted by reference to Fig. 3 that as the spring slides member 7 outwardly again the pin 21 will be automatically reintroduced in opening 12 by the pressure exerted by spring 20.

To hold the switch open after being man- 55 ually opened, I prefer the following construction:—45 is a gravity catch pivoted to rail 2 and provided with a beveled free end 46 disposed toward and in the same vertical plane as a pin 47 projecting laterally from member 60 7 and the member 13, it being noted that when the said cross-bar is contracted, said pin is adjacent to the inner end of member 13. As the bar as a whole is moved inward 65 the pin and member 13 successively engage and lift the gravity catch until it rests upon

said member, dropping to its original position when the movement of the bar is reversed. When member 7 is moved inward alone, its pin 46 engages and lifts the catch and then the latter drops outward of the 70 pin and holds the switch open and thus relieves the operator of holding it open until the approaching train traveling on the main track in the opposite direction to that indicated by the arrow (Fig. 1) passes, the point 75 of the switch, said train immediately after passing such point engaging the right-hand lever 37 and depressing the same and the companion lever 37 and moving member 13 inward to reelevate the catch so as to permit 80 the cross bar as a whole to be returned to its original position by spring 11, after the train clears the said companion lever 37.

If desired the spring-actuated pin 21 for locking the two members of the extensible 85 cross-bar together and the lever 19 for withdrawing said pin 21, may be omitted as the action of spring 11 is sufficient to normally hold the said bar contracted and the switch closed. 90

From the above description it will be apparent that I have produced a railway switch which can be opened by a train or manually and which will automatically close when no longer resisted by an overpowering 95 force, it being further noted that the switchman by the proper manipulation of lever 26 may assist the spring 11 in the closing operation if desirable or necessary.

It is to be understood, of course, that I re- 100 serve the right to make such changes in the form, proportion, detail construction and arrangement of the parts as properly fall within the principle of construction involved.

Having thus described the invention, what 105 I claim as new and desire to secure by Letters Patent, is:—

1. In a railway switch, a main track section comprising a stationary rail and a movable rail, a switch track section comprising a 110 stationary rail and a movable rail, a cross-bar connecting the movable rails together, and provided with rack-teeth, a pair of levers 115 suitably pivoted at their remote ends and pivoted together at their contiguous ends and sloping upward toward the last-named ends to a point above the contiguous stationary main track rail, a vertical rack-bar movable with said levers, a shaft, a gear wheel secured upon one end of the shaft and 120 engaging said rack-bar, a second gear wheel secured upon said shaft and engaging the rack-teeth of said cross-bar, and yielding means for resisting the depression of said levers and the opening of the switch. 125

2. In a railway switch, a main track section comprising a stationary rail and a movable rail, a switch track section comprising a 130 stationary rail and a movable rail, a cross-bar consisting of an inner member connect-

- ing the movable rails and an outer member 5 slidably connected to the inner member, a spring tending to hold said members pressed endwise together and the switch closed, a switch-stand provided with a movable arm, a link pivotally connecting said arm with the said inner member, a pin projecting from said inner member and a bevel-end catch suitably pivoted and adapted when the 10 switch-stand is operated to open the switch, to be pushed aside by said pin and then drop behind it to lock the switch open.
3. In a railway switch, a main track section comprising a stationary rail and a movable rail, a switch track section comprising a stationary rail and a movable rail, a cross bar 15 consisting of an inner member connecting the movable rails and an outer member slidably connected to the inner member, a spring 20 tending to hold said members pressed endwise together and the switch closed, a switch-stand provided with a movable arm, a link pivotally connecting said arm with the said inner member, a pin projecting from said 25 inner member, a bevel-end catch suitably pivoted and adapted when the switch-stand
- is operated to open the switch, to be pushed aside by said pin and then drop behind it to lock the switch open, and means to operate the said outer member and cause the same 30 to lift said catch to inoperative position.
4. In a railway switch, a main track section comprising a stationary rail and a movable rail, a switch track section comprising a stationary rail and a movable rail, a cross-bar 35 consisting of an inner member connecting the movable rails and an outer member slidably connected to the inner member, a spring-actuated pin locking said members rigidly together, means to unlock said pin, a switch-stand embodying a shaft provided with a handle and a crank arm, a link pivotally connecting the crank arm and the inner member of the cross-bar, and a spring for resisting movement of the inner member tending 40 to open the switch.

In testimony whereof I affix my signature, in the presence of two witnesses.
